(57) **CLAIM**

The ornamental design for a yoga wheel, as shown and described.

DESCRIPTION

FIG. 1 is a perspective view of a first embodiment of a yoga wheel, taken from the front.

FIG. 2 is a front view of the first embodiment of the yoga wheel of FIG. 1;

FIG. 3 is a back view of the first embodiment of the yoga wheel of FIG. 1;

FIG. 4 is a left-side view of the first embodiment of the yoga wheel of FIG. 1.

FIG. 5 is a right-side view of the first embodiment of the yoga wheel of FIG. 1.

FIG. 6 is a top view of the first embodiment of the yoga wheel of FIG. 1.

FIG. 7 is a bottom view of the first embodiment of the yoga wheel of FIG. 1.

FIG. 8 is a top perspective view of a second embodiment of yoga wheel, take from the side;

FIG. 9 is a front view of the second embodiment of the yoga wheel of FIG. 8;

FIG. 10 is a back view of the second embodiment of the yoga wheel of FIG. 8;

FIG. 11 is a left-side view of the second embodiment of the yoga wheel of FIG. 8;

FIG. 12 is a right-side view of the second embodiment of the yoga wheel of FIG. 8;

FIG. 13 is a top view of the second embodiment of the yoga wheel of FIG. 8;

FIG. 14 is a bottom view of the second embodiment of the yoga wheel of FIG. 8; and,

FIG. 15 is an exploded view of the pattern on the exterior surface of the second embodiment of the yoga wheel of FIG. 8.

The dashed broken lines depict portions of the yoga wheel which form no part of the claimed design. The dot-dashed lines depict the claimed design.

(Continued)

broken lines represent boundaries of the claimed yoga wheel and form no part of the claimed design.

1 Claim, 15 Drawing Sheets
